UNITED STATES PATENT OFFICE.

ADOLPH NYDEGGER, OF MILWAUKEE, WISCONSIN, ASSIGNOR TO C. H. & E. MANUFACTURING COMPANY, OF MILWAUKEE, WISCONSIN, A CORPORATION OF WISCONSIN.

PLASTER-MIXER.

1,131,260.

Specification of Letters Patent.

Patented Mar. 9, 1915.

Application filed November 4, 1914. Serial No. 870,178.

To all whom it may concern:

Be it known that I, ADOLPH NYDEGGER, a citizen of the United States, and resident of Milwaukee, in the county of Milwaukee and 5 State of Wisconsin, have invented new and useful Improvements in Plaster-Mixers, of which the following is a description, reference being had to the accompanying drawings, which are a part of this specification.

10 This invention has for its object to provide a machine for mixing plaster, mortar and the like and consists of a cylindrical drum containing stationary and rotary mixing blades or paddles, the rotary blades being driven from beneath the drum so as to leave the upper end of the drum open for admitting the materials to be mixed, said drum being provided with a sliding gate on the bottom thereof for permitting the mixture to be discharged therefrom.

Another object of the invention is to perfect details of construction of such a mixer in order that the mixing operation may be quickly and thoroughly performed and in 25 order that the mixing blades may be quickly removed for cleaning the drum.

With the above and other objects in view the invention consists in the plaster mixer as herein claimed and all equivalents.

30 Referring to the accompanying drawings in which like characters of reference indicate the same parts in different views: Figure 1 is a plan view of a plaster mixer exemplifying the invention; Fig. 2 is a central sectional side view thereof; Fig. 3 is a central sectional view on a plane at right angles to the plane of Fig. 2. Fig. 4 is a detailed view of the rack and pinion means for controlling the discharge from the drum; and Fig. 5 is 40 a detailed sectional view thereof.

In these drawings 10 indicates a truck mounted on wheels 11 so as to be readily moved from place to place and 12 is a frame mounted thereon having rigidly fastened to 45 it a cylindrical drum 13 having an upstanding tubular sleeve 14 at its center passing through an opening in the bottom of the drum and fixed in place by means of nuts 15 threaded thereon above and below the bottom of the drum. A square shaft 16 fits within the sleeve 14 and is journaled within

a self alignment thrust bearing 17 on the frame with a beveled gear 18 between the bearing and the drum. A shaft 19 journaled on the frame carries a beveled pinion 20 meshing with the beveled gear 18 and at its outer end is a sprocket wheel 21 driven by a chain 22 from a sprocket wheel 23 on a jack shaft 24 which is journaled across the frame. A gas engine or other motor on the truck 60 drives the jack shaft 24 through a chain 25 engaging a sprocket wheel 26 on the shaft and having driving connection with the shaft by means of a suitable clutch 27 operated by a lever 28. At its upper end a square 65 shaft 16 is turned down to fit within a bearing 28 carried by a spider frame 30 which preferably consists of three arms as shown clamped to the edge of the drum by means of clamping nuts 30' threaded on studs 31, 70 the arms of the spider frame having slots opening in the direction of the turning of the shaft to facilitate their ready detachment when the nuts are loosened without rendering them liable to disconnection during the operation of the machine. Stationary mixing rods or paddles 32 are secured to 75 the two arms of the spider frame which are diametrically opposite and project downwardly into the drum and are preferably 80 square in cross section with their diagonals set radial to the axis of the drum. A socket 33 having a circular bore to fit the reduced turned end of shaft 16 and a lower circular bore to fit around the sleeve 14 and an intermediate portion square in cross section to fit 85 between the upper end of the square portion of shaft 16 so as to be positively connected with the shaft and turned therewith carries a downwardly extending arm 34 spaced 90 from the sleeve 14 with an outwardly extending scraping blade 35 engaging the bottom of the drum or traveling close thereto to scrape the material from the bottom of the drum, its front edge being preferably 95 beveled for that purpose. At its upper end the scraper blade 35 carries an upwardly extending scraper rod 36 which is beveled to form a knife edge scraping against or traveling close to the walls of the drum to 100 scrape material therefrom and another mixing rod 37 projects upwardly from the

scraper blade 35 at a position to travel between the stationary mixing rods 32.

A discharge opening is formed in the bottom of the drum with a spout 38 to deflect the discharged material away from the driving gear and into a wheel-barrow or the like beneath and this opening is normally closed by a sliding gate 39 which fits between guides 40 on the bottom of the drum and carries a rack 41 meshing with a pinion 42 on a shaft 43 journaled beneath the drum with a crank handle 44 by means of which it is turned for opening and closing the sliding gate. A chain 45 connecting the sliding gate with the drum serves to limit the opening movement of the sliding gate and in order that the edges of the discharge opening may not form shoulders in the bottom of the drum against which gravel or the like may engage for interfering with the movements of the scraper blade 35 a protecting plate 46 of the thickness of the bottom of the drum and corresponding in size to the discharge opening is mounted on the sliding gate 39 to just fit the discharge opening when the sliding gate is closed.

A feed spout 47 may be suitably mounted at one side of the drum to guide the feed of material into that portion of the open upper end of the drum which is without one of the arms of the spider frame 30. When the materials are placed in the drum the turning of the shaft 16 causes the arm 34, the scraper blade 35 and the mixing rods or paddles 36 and 37 to turn around the drum and cooperate with the stationary mixing rods 32 to effect a thorough and complete and rapid mixture, the scraper blade 35 and the scraper rod 36 scraping the material away from the bottom and the walls of the drum respectively so that the mixing operation is effected evenly throughout the material. By turning the crank handle 44 the sliding gate 39 may be opened to discharge the mixture into a receptacle below.

It is very important in a plaster mixer that the parts should be thoroughly cleaned each night as particles of set plaster will cause the fresh mixture to set more quickly in localized spots and consequently provision is made in the plaster mixer of this invention for a quick and easy removal of the parts for cleaning. It is only necessary to loosen the nuts 30' when the spider frame 30 may be turned slightly to disengage the slotted ends of its arms from the studs 31 and it may then be lifted off of the shaft 16 for cleaning the mixing rods 32. The socket 33 may also be lifted off of the shaft 16 for cleaning its parts and the drum without obstruction therein may be flushed with a hose and readily cleaned so that all operating parts are cleaned without difficulty.

It is obvious that the mixer of this inven-

tion is not limited to the use for mixing 65 plaster, but may be used in mixing mortar, cement and the like.

What I claim as new and desire to secure by Letters Patent is:

1. A plaster mixer comprising a vertical 70 fixed drum having an upstanding central sleeve, a suitably driven shaft turning within the sleeve and having an angular shoulder, a socket removably fitting on the angular shoulder of the shaft, a downwardly ex- 75 tending arm on the socket, upstanding rotary mixing rods carried by the arm, a frame removably clamped to the drum and having a bearing receiving the end of the shaft, and stationary mixing rods mounted 80 on the frame out of the path of travel of the rotary mixing rods.

2. A plaster mixer, comprising a vertical stationary cylindrical drum, a tubular sleeve fixed in the center of the bottom of the drum 85 and extending upwardly therein, a suitably operated shaft within the sleeve having an angular shoulder projecting thereabove, a frame removably clamped to the upper end of the drum and having a bearing receiving 90 the upper end of the shaft, a socket removably fitting on the shaft and engaging the driving shoulder thereof to be turned thereby, an arm projecting downwardly from the socket, a scraper blade carried by the arm 95 for scraping the bottom of the drum, an upstanding scraper rod at the end of the scraper blade for scraping the side walls of the drum, and downwardly extending mixing rods on the frame. 100

3. A plaster mixer, comprising a vertical cylindrical stationary drum, an upstanding tubular sleeve fitting in a central opening in the bottom thereof, a suitably driven square shaft fitting within the sleeve with a reduced upper end circular in cross section, a spider frame having arms releasably clamped to the upper edge of the drum and provided with a bearing to receive the reduced end of the shaft, stationary mixing 110 rods projecting downwardly from the arms of the spider frame, a socket removably fitting on the upper end of the square portion of the shaft and around the reduced portion of the shaft and around the upper end of 115 the sleeve, a downwardly projecting arm on the socket spaced from the sleeve, a scraper blade carried by the lower end of the arm to scrape the bottom of the drum, an upstanding scraper rod carried by the upper end of 120 the scraper blade to scrape the inner walls of the drum, and an upstanding mixing rod secured to the scraper blade and traveling between the stationary mixing rods. 125

4. A plaster mixer, comprising a stationary vertical cylindrical drum, an upstanding tubular sleeve in the bottom of the drum, a suitably driven shaft turning within the

sleeve, a socket removably secured to the shaft above the sleeve, upstanding mixing rods carried by the socket, clamping bolts at the edge of the drum, a frame fitting on the edge of the drum and having slots extending in the rotary direction of the shaft for engaging the clamping bolts, a bearing carried by the frame and receiving the upper end of the shaft, and stationary mixing rods

carried by the frame and projecting into the drum to coöperate with the upstanding mixing rods.

In testimony whereof, I affix my signature, in presence of two witnesses.

ADOLPH NYDEGGER.
